DOOR SECURING MEANS

Bert R. Jones, West Haven, Conn.

Application December 23, 1931, Serial No. 582,755

3 Claims. (Cl. 292—202)

This invention relates to improvements in door securing means especially adapted for use in connection with double doors of railway refrigerator cars.

5 One object of the invention is to provide a door latching means for double hinged doors of refrigerator cars, whereby both doors are held closed and secured against accidental opening.

Another object of the invention is to provide 10 in combination with the usual operating and locking means for holding the double doors of refrigerator cars closed, latching means for both doors by which the door first closed is secured against opening movement during actuation of the operating and locking means coacting with the other door, and wherein said latching means is also employed to secure the last named door in locked position, thereby providing a safety device to prevent accidental opening of said door with 15 resultant outward swinging movement of the lever of the operating and locking means in case the door has not been properly locked in closed position.

Other objects of the invention will more clearly appear from the description and claims hereinafter following.

In the drawing, forming a part of this specification, Figure 1 is an elevational view of the side wall of a refrigerator car, illustrating my 20 improvements in connection therewith. Figure 2 is an enlarged, detailed, side elevational view of a pivoted latch member employed in connection with my improvements. And Figure 3 is an edge elevational view of the latch member shown in Figure 2, looking from the left in said figure.

35 In said drawing, 10 designates the side wall of a refrigerator car, which wall is provided with the usual door opening 11. The door opening 11 is closed by swinging doors 12 and 13, which are hinged along their vertical outer edges to the door frame by means of the usual hinge members 14—14 and 14—14. The doors 12 and 13 are of the usual type employed in connection with refrigerator cars, having their inner meeting edges beveled and overlapping, as clearly shown in 40 Figure 2 of Patent No. 1,193,414 granted August 1, 1916, to John F. O'Connor. The door 12 has a rotary combined actuating and locking bar A mounted thereon, which has keeper engaging 45 crank members B—B at the top and bottom ends thereof engaging keepers C—C mounted on the door frame. The bar is journaled in top and bottom brackets D—D fixed to the door 12 and is operated by a pivoted lever E, which is latched in 50 closed position by the locking member G. The

combined actuating and locking means comprising the bar A, keeper engaging cranks B—B, keepers C—C, journal brackets D—D, operating lever E, and locking means G, is well known in the art and needs no further description, the same being fully disclosed in Patent No. 1,193,414 hereinbefore mentioned.

In carrying out my invention, I provide a pivoted latch member H, which is mounted on the lower keeper bracket C and engages over protecting wear plates K and M. The lower keeper engaging bracket C is provided with an extension 20, which is forked at its outer end, as indicated at 21, said forked portion receiving the lower end of the latch member H so as to support the same 15 for swinging movement. A pivot member 22 in the form of a bolt or lag screw is employed to connect the latch H to the bracket C, this pivot member extending through aligned openings in the forked section 21 of the bracket C and a pivot 20 opening 23 at the bottom end of the latch member H. The latch member H is of angular outline, as most clearly shown in Figures 1 and 2, comprising an arm 24 forming the main body portion of the latch and a laterally extending integral finger 25 at the upper end of said arm, said finger being disposed at an angle to the arm which is greater than 90°, whereby the finger 25 is disposed in substantially horizontal position when the latch member is in locking relation with respect to the doors 12 and 13, as shown in Figure 1.

The wear plate K is secured to the lower inner right-hand corner of the door 13, as shown in Figure 1, while the wear plate M is secured to the lower inner corner of the door 12.

35 As will be clear upon reference to O'Connor Patent No. 1,193,414, the door which carries the actuating and locking means is the door closed last and has the beveled inner edge thereof overlapping the other door.

40 In closing the doors, the operation is the same as that described in said O'Connor patent, the door 13 being first brought to closed position and the latch H swung in overlapping relation with respect to the plate K. At this time the 45 latch H is not moved a sufficient distance to engage with the door 12. The door 12 is then swung to partly closed position so as to bring the keeper engaging members B—B of the actuating and locking means into proper position 50 to effect engagement thereof with the keepers when the bar A is rotated by the lever E. Upon rotation of the bar A, the door 12 will be forced to tightly closed position. When the door 12 has been thus closed, the latch member H is 55

swung to its limit in a right-hand direction, as viewed in Figure 1, thereby engaging the finger 25 thereof over the corner plate M of the door 12. As will be evident, the latch H in the position shown in Figure 1 secures both doors 12 and 13 in closed position and is maintained in that position due to the action of gravity. This is of especial advantage as a safety device for holding the doors closed when the operator has neglected to properly close the doors by the combined 10 actuating and locking means, not having latched the lever E by means of the locking device G. This frequently takes place when the cars are not loaded and the doors are closed without sealing the same by the usual sealing means employed in connection with the locking member G and the lever E. Inasmuch as my improved latching means secures the door 12 in closed 15 position at all times, regardless of the proper securing of the combined actuating and locking means, accidental loosening and rotation of the locking bar, due to vibrations of the car in transit, are eliminated, thereby preventing accidental opening of the door and protecting both the operating means and the door 12 from damage. Such damage would naturally occur due to side-swiping by another car when the door is partially open.

In opening the doors, the latch H is swung to the left, as viewed in Figure 1, so as to clear the edge of the door 12. The combined actuating and locking means is then operated by swinging the lever E so as to rotate the bar A. By the action of the combined actuating and locking means the door 12 is forced partly open. After partial opening of the door, the same may be directly swung to fully open position by the attendant. As will be obvious, the door 13 may be then opened after completely disengaging the latch H from the lower corner thereof.

I have herein shown and described what I now consider the preferred manner of carrying out my invention, but the same is merely illustrative and I contemplate all changes and modifications that come within the scope of the claims appended hereto.

I claim:

1. In a door securing means for a refrigerator car having double doors hinged along their outer edges, the inner edge of one door overlapping the inner edge of the other door when the doors are closed, the combination with a supporting bracket fixed to the car below the bottom edges

of the doors; of a latch arm pivoted on said bracket for swinging movement in a plane parallel to the plane of the doors when closed, said latch arm being of such a width that it overlaps the lower inner edges of both doors when said latch is in locking position, said latch arm being swingable from said locking position to an extent to clear both doors, said latch arm being further swingable to a location between said locking position and the position in which it clears both doors to engage over the lower inner corner of the overlapped door only to hold the latter closed while the overlapping door is forced to closed position.

2. In a door securing means for a refrigerator car having double doors hinged along their outer edges, the inner edges of said doors being beveled and said inner edge of one door overlapping the inner edge of the other door when the doors are closed, the combination with a supporting member fixed to the car below the doors and adjacent to the meeting inner edges thereof; of a latch arm pivoted to said supporting member for swinging movement in a plane parallel to the plane of the doors when closed, said latch arm being of a width to overlap the lower inner corners of both doors when said latch is in locking position to hold said doors closed, said latch arm being retractable to a position to entirely clear both of said doors.

3. In a door securing means for a refrigerator car having double doors hinged along their outer edges, the inner edges of said doors being beveled and said inner edge of one door overlapping the inner edge of the other door when the doors are closed, the combination with a supporting member fixed to the car below the doors and adjacent to the meeting inner edges thereof; of a latch member comprising an arm having an angular extension at one end and having the other end pivoted on said support to permit swinging movement of said latch member in a plane parallel to the plane of said doors when closed, said latch member when in locking position having the arm thereof engaging over the lower inner corner of one of said doors and the angular extension thereof engaging over the lower inner corner of the other door, said latch member being movable to a position to overlap the lower corner of one of said doors only and being further movable to completely clear both doors.

BERT R. JONES.
